CERVICAL SPLINT

Thomas C. Ward, Marlin, Tex.

Application December 17, 1937, Serial No. 180,444

4 Claims. (Cl. 128—87)

This invention relates to an improvement in cervical splints for supporting the head in the treatment of fracture or fractures of the cervical vertebrae.

5 One of the objects of the invention is to provide a supporting structure which may be fitted readily to splints of various sizes and ages.

Another object of the invention is to provide 10 simple, convenient and efficient means for freely 10 and comfortably supporting the head.

15 A further object is to provide a device which may be applied to a patient's head by a physician with little, if any, movement of the patient or his head.

20 Further objects and advantages will be apparent from the hereinafter detailed description.

These and other objects are attained by the device illustrated in the accompanying drawings, in which—

25 Figure 1 is a perspective front view of a splint in which the invention is applied to the patient;

Fig. 2 is a perspective rear view of the splint in which the invention is embodied applied to the patient;

30 Fig. 3 is a side elevation view of the front portion of the splint;

Fig. 4 is a side elevation view of the rear portion of the splint;

Fig. 5 is a plan view of the chin plate of the 35 splint;

Fig. 6 is a plan view of the neck splint of the splint;

Fig. 7 is a detailed view of the clamping means for the angle irons;

35 Fig. 8 is a section view of the adjustable pivot for the angle irons and the front portion;

Fig. 9 is a section of the means shown in Figure 1 on the line 9—9 for securing the strap buckles to the front portion;

40 Fig. 10 is a cross section taken on line 7—7 of Figure 3; and

Fig. 11 is a view of an end of one of the irons.

In the invention as illustrated in the accompanying drawings, there is disclosed a preferred 45 construction of a device which comprises a front breast section 1 composed of a "yoke-shaped" metal strip 2 provided with suitable padding material 3. The metal strip 2 is made of light-weight metal which gives it a flexibility to thereby 50 enable it to give way to the contours of the patient's body portion. This is desirable particularly since the yoke-shaped design of the front breast section enables the splint to be used upon a female patient without possible injury, 55 pain, harm or discomfort to the breast portion

of the patient. The padding material 3 is secured to the metal strip 2 by thread or other suitable means which passes through apertures 4 provided at intervals along the outer edges of metal strip 2.

5 Tongue buckles 4a, 4b (Fig. 9) are slipped through a flexible band 5 which band is flattened and secured by suitable means 6, such as a rivet, to the lower end portion 7 of the metal strip 2. A single unit buckle 9 is secured by means of 10 an elastic or flexible material 10 to each arm 8 of the yoke portion.

15 At the center portion 11 of the yoke-shaped plate 2 there are secured two small angle irons 12 which are positioned in spaced relationship 15 and provided with coinciding apertures 13 in their adjacent sides for the passage of bolt screw 14.

An iron 15 is pivotally mounted between the angle irons 12 as shown in Fig. 1 by means of screw bolt 14 which passes through apertures 13 20 of the angle irons and aperture 14a in iron 15. This iron 15 is twisted a short distance from its end which is mounted between angle irons 12, as shown at 16, so that its flat sides 17 and 18 are at right angles to one another. The longer 25 flat surface 18 of the iron 15 has an aperture 19 for a purpose hereinafter mentioned. A second iron 20 of similar shape to iron 15 is provided with aperture 21 and is placed adjacent to iron 15 as shown in Fig. 1. Screw bolts 23 30 and 24 are passed through apertures 19 and 21 of the irons 15 and 20 in order that the irons may be adjustably mounted with respect to one another. The irons 15 and 20 may be tapered, straight or otherwise shaped and secured together, if desired, in order to give a particular adjustment which may be necessary for some special patient.

35 A chin-plate 25 comprising a metal strip 26 which is suitably made from flexible metal in 40 order to conform generally to the shape of the chin and provided with suitable padding material 27 for the comfort of the user, has two small angle irons 28 and 29 secured by solder or other suitable means to the lower central portion 29 45 of the chin-plate. Angle irons 28 and 29 are provided with apertures 30 for the passage of a screw bolt 30a. Iron 20, previously referred to is pivotally mounted between irons 28 and 29 by means of screw bolt 30a which passes through 50 apertures 30 of the angle irons 28 and 29 and aperture 31 in iron 20. Suitable buckles 32 are secured by suitable means to the side portion 33 of the chin-plate 25 for the fastening of adjustable strips 34 and 35 hereinafter referred to. 55

It will be seen that the section of the cervical splint thus far described enables one to vary the position of the chin-plate to various angles as may be desired, so that it may be used on all types of persons, both large or small, old or young, and male or female.

A rear plate section 36, as shown in Fig. 2, is flexibly and adjustably secured to the front breast section 1 by straps 74 or other means 10 hereinafter mentioned. The rear plate 36 comprises a "yoke-shaped" metal strip 37 provided with suitable padding material 38, which padding material is secured by threads or other means through apertures provided in metal strip 37. 15 Tongue buckles 40a, 40b are secured by flexible bands 41 to the lower portion 42 of the metal strip 37 in a manner similar to the buckles 4 described and shown in Fig. 1. Buckles 45 and 46 are secured by flexible materials 47 and 48 20 to each arm 49 and 50 of the yoke-shaped metal strip 37 as shown in Fig. 4. Small angle irons 51 and 52 are secured by solder or other means to the center portion 53 of the rear plate 36.

An iron 54 is pivotally mounted between angle 25 irons 51 and 52 by means of screw bolt 55 which passes through aperture 56 in iron 54. This iron 54 is twisted in the same manner as iron 15, shown in Fig. 1, in order to provide flat sides 57 and 58. The longer flat surface 58 of the iron 30 54 has an aperture 59. Iron 55, identical in structure to the iron 54, is provided with flat sides 60 and 62 and aperture 62a. The irons 54 and 55 are joined together by means of screw bolts 63 and 64, which pass through apertures 35 59 and 62 (Fig. 4) of the irons.

A neck-splint 65 comprises a metal strip 66 shaped in the fashion of a "butterfly" 67. Metal strip 66 is made of flexible metal and is bent slightly in contour to conform generally to the 40 back of a person's neck. Appropriate padding material 68 is secured to the metal strip 66 for the comfort of the patient. The metal strip 66 is provided with angle irons 69 and 70 which are shaped in the same manner as angle irons 28 and 45 29 of the chin-plate 25. These angle irons are provided with apertures 71 and 72 (Fig. 6). The irons 69 and 70 having been joined together by means of screw bolts 63 and 64 are pivotally mounted to the neck-splint 65 by means of screw 50 bolt 73.

The butterfly strip 67 is provided with buckles 75 secured by flexible means 76 to the lower end portion of the butterfly strip. These buckles are used for adjustably securing straps for varying 55 the distance and position of the neck-splint and the chin-plate aforementioned.

Having described in some detail the static structure of the front and rear portions of the splint, attention is now called to the flexible 60 means used to properly adjust the aforementioned sections in order that they will properly protect a patient suffering from a broken cervical vertebra.

As aforementioned, each yoke section 2 and 65 37 is provided at its base portion with buckles 4a, 4b and 40a, 40b. Suitable flexible strips 74 are used to connect together the front and rear plates of the splint in any desired position and tightness for conformity of the splint to the patient's body, neck and head. Similar flexible straps 61 (Figs. 1 and 2) are used over the shoulders of a patient and secured to buckles 9 and 45 and 46 on the arm portions of the front and rear plates. These straps are likewise adjusted 70 75 to properly position the upper portion of the

front and rear plates for better conformity to the patient's body, head and neck. Small narrow straps 34 and 35 are adjustably secured to the buckles 32 and 75 for adjusting the chin-plate and the neck-splint to conform to the contours 5 of the patient.

It will be readily appreciated that by freely adjusting the various straps to conform to the dimension of a patient, that various adjustments can be made which will securely position a patient's head in relationship to his body and neck without any appreciable movement of the patient's body, neck or head.

It will also be noted that the several irons 15, 20, 55 and 54 are adjustable (set screws 23, 24, 15 63, and 64) in sets in order that the chin-plate and/or neck-splint may be adjusted to suit the patient's head contours. By loosening the several screw bolts 30a and 73 the chin-plate and/or neck-splint may be tilted and adjusted for the 20 convenience of the patient.

The above mentioned adjustable features provide a cervical splint which may be applied to a patient while the patient is in bed, and while the patient's head has a halter on, without the 25 removal of the halter or lessening any traction on the neck made by the head halter, which has heretofore been impossible due to the shape and structure of previous cervical splints.

The invention herein described also provides 30 a cervical splint which may be adjusted from time to time as the patient improved, to thereby vary the tension placed upon the various portions of the patient's body, neck and head to expedite the recovery of the patient from a broken cervical 35 vertebra.

An additional advantage of the present invention is the provision of a splint which is not moved out of position by the slight change in the position of the patient's shoulders and arms. The 40 movement of the shoulders and arms of the patient have heretofore disturbed the position of the cervical splint, and thereby added to the discomfort of the patient, and at times severely injured the patient due to the fact that the known 45 splints were mounted upon the patient's shoulders and were moved by each and every movement of the arms and shoulders of the patient. This disadvantage as heretofore mentioned, is overcome by the use of the present invention. 50

The invention is capable of modifications to its several parts without material departure from its scope or spirit as defined in the appended claims. For example, various sizes or odd sizes, such as one large, one small, of front and rear sections 55 may be used and interchanged as desired in order that the cervical splint may properly fit persons of irregular or deformed bodies.

Having thus described my invention, what I claim as new and desire to secure by Letters 60 Patent of the United States is:

1. A cervical splint comprising a front section adapted to rest upon substantially non-moving bones and muscles of the chest of the wearer, a rear section independent of said front section and adapted to rest upon substantially non-moving bones and muscles of the back of the wearer, said front and rear sections comprising flexible metallic plates adapted to bend to the contours of the chest and back of the wearer, fastening 70 means secured to said front and rear sections, straps secured to said fastening means and adapted to join said front and rear sections in spaced relationship, overlapping irons pivotally secured in independent sets to said front and rear 75

- sections, said irons provided with longitudinal slots and screw bolts and adapted to be adjusted to the size and shape of the wearer, a chin-plate pivotally secured to said set of overlapping irons 5 secured to said front section only, buckling means secured to said chin-plate, a neck-splint pivotally secured to the second independent set of said overlapping irons, said second set of overlapping irons being pivotally secured to said rear section 10 only and flexible means adjustably secured to said buckling means of said chin-plate and said neck-splint and adapted to join said chin-plate and neck-splint in spaced relationship whereby said front and rear sections and said chin plate and 15 said neck splint are adapted to be adjusted independent of each other to conform to the size and shape of the wearer.
2. A cervical splint comprising a front section adapted to rest upon substantially non-moving 20 bones and muscles of the chest of the wearer, a rear section independent of said front section and adapted to rest upon substantially non-moving bones and muscles of the back of the wearer, said front and rear sections comprising flexible 25 yoke-shaped metallic plates adapted to bend to the contours of the chest and back of the wearer, fastening means secured to said front and rear sections, straps adjustably secured to said fastening means adapted to join said front and rear 30 sections in spaced relationship, overlapping irons pivotally secured in independent sets to said front and rear sections, said irons provided with longitudinal slots and screw bolts and adapted to be adjusted to the size and shape of the wearer, a 35 chin-plate pivotally secured to said set of overlapping irons secured to said front section only, buckling means secured to said chin-plate, a neck-splint pivotally secured to the second set of said overlapping irons, said second set of overlapping irons being pivotally secured to said rear section 40 only and flexible means adjustably secured to said buckling means of said chin-plate and said neck-splint and adapted to join said chin-plate and neck-splint in spaced relationship whereby 45 said front and rear sections and said chin plate and said neck splint are adapted to be adjusted independent of each other to conform to the size and shape of the wearer.
3. A cervical splint comprising a front section 50 adapted to rest upon substantially non-moving bones and muscles of the chest of the wearer, a rear section independent of said front section and adapted to rest upon substantially non-moving bones and muscles of the back of the wearer, said 55 front and rear sections comprising flexible metallic plates adapted to bend to the contours of the chest and the back of the wearer, fastening means secured to said front and rear sections, two sets of straps secured to said fastening means
- and adapted to join said front and rear sections in spaced relationship, one set of said straps adapted beneath the armpits of the wearer and the other set of straps adapted over the shoulder of the wearer, over-lapping irons pivotally secured 5 in independent sets to said front and rear sections, said irons provided with longitudinal slots and screw bolts and adapted to be adjusted to the size and shape of the wearer, a chin-plate pivotally secured to said set of over-lapping irons 10 secured to said front section only, buckling means secured to said chin-plate, a neck splint pivotally secured to second independent set of said over-lapping irons, said second set of over-lapping irons being pivotally secured to said rear section 15 only, and flexible means adjustably secured to said buckling means of said chin-plate and said neck splint and adapted to join said chin-plate and said neck splint in spaced relationship, whereby, said front and rear sections and said chin-plate and said neck splint are adapted to be 20 adjusted independent of each other to conform to the size and shape of the wearer.
4. A cervical splint comprising a front section adapted to rest upon substantially non-moving 25 bones and muscles of the chest of the wearer, a rear section independent of said front section and adapted to rest upon substantially non-moving bones and muscles of the back of the wearer, said front and rear sections comprising flexible yoke-shaped metallic plates adapted to bend to the contours of the chest and the back of the wearer, fastening means secured to said front and rear sections, two sets of straps adjustably secured to said fastening means and adapted to join said 30 front and rear sections in spaced relationship, one set of said straps adapted beneath the armpits of the wearer and the other set of straps adapted over the shoulder of the wearer, over-lapping irons pivotally secured in independent sets to 35 said front and rear sections, said irons provided with longitudinal slots and screw bolts and adapted to be adjusted to the size and shape of, the wearer, a chin-plate pivotally secured to said set of over-lapping irons secured to said front 40 section only, buckling means secured to said chin-plate, a neck splint pivotally secured to second independent set of said over-lapping irons, said second set of over-lapping irons being pivotally secured to said rear section only, and flexible 45 means adjustably secured to said buckling means of said chin-plate and said neck splint and adapted to join said chin-plate and said neck splint in spaced relationship, whereby, said front and rear sections and said chin-plate and said neck splint are adapted to be adjusted independent of each other to conform to the size and shape of the wearer.

THOS. C. WARD.
